Primary Examiner — Rhea Shields(74) *Attorney, Agent, or Firm* — Louis C. Paul & Associates, PLLC(57) **CLAIM**

The ornamental design for a lint broom, as shown and described.

DESCRIPTION

FIG. 1 is a top view of the lint broom.

FIG. 2 is a bottom view of the lint broom.

FIG. 3 is a front view of the lint broom.

FIG. 4 is a rear view of the lint broom.

FIG. 5 is a left side view of the lint broom; the right view being a mirror image thereof; and,

FIG. 6 is a perspective view of the lint broom.

In the drawings, the broken lines are for the purpose of illustrating environment only and form no part of the claimed design.
